CLAIM

The ornamental design for a shoe box with integral erectable display stand, as shown and described.

DESCRIPTION

FIG. 1 is an end, side and top perspective of a shoe box with integral erectable display stand showing my new design;

FIG. 2 is an end elevational view, the opposite end being the same in appearance;

FIG. 3 is a side elevational view, the opposite side being the same in appearance;

FIG. 4 is a top plan view, the bottom being plain and unornamented; and,

FIG. 5 is a top perspective view thereof with the integral display stand in collapsed condition.

*FIG. 1**FIG. 2**FIG. 3**FIG. 4*

FIG. 5
